METHOD FOR REDUCING THE SURFACE-ADHESIVENESS OF ARTICLES

Filed Aug. 17, 1944

UNITED STATES PATENT OFFICE

2,438,622

METHOD FOR REDUCING THE SURFACE
ADHESIVENESS OF ARTICLESRobert H. Sperzel, Hamden, Conn., assignor to
The Whitney Blake Company, Hamden, Conn.,
a corporation of Connecticut

Application August 17, 1944, Serial No. 549,939

6 Claims. (Cl. 117—139)

1

The present invention relates to improvements in methods for reducing the surface-adhesiveness of articles having tacky surfaces such, for instance, as wire insulated with rubber or the like, elastic strands, etc.

One of the objects of the present invention is to provide a simple, reliable and effective method for reducing the surface-adhesiveness of articles having tacky surfaces.

Another object of the present invention is to provide a superior method of the character referred to, and characterized by minimum consumption of adhesiveness-reducing materials.

A further object of the present invention is to provide a superior method for reducing the surface-adhesiveness of articles having tacky surfaces, and characterized by avoidance of air pollution.

Still another object of the present invention is to provide a superior method of the character referred to whereby the adhesiveness of the surfaces of tacky articles may be reduced without requiring the employment of hazardous and disagreeable dusty materials.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of one form of apparatus suitable for carrying out the present invention;

Fig. 2 is an end view thereof; and

Fig. 3 is a view in vertical central-longitudinal section taken on the line 3—3 of Fig. 2, but on a larger scale.

The apparatus illustrated in the accompanying drawings is designed and adapted to provide for the production of a large mass of bubbles of any suitable froth-producing and adhesiveness-reducing material such, for instance, as water-soluble soaps, water-insoluble soaps, sulphonated alcohols, pine oil, etc.

The apparatus illustrated is in the form of an elongated rectangular tank 10 which may be produced of any suitable material such, for instance, as sheet metal, and in the instance shown, in-

2

cludes a front-wall 11, a rear-wall 12 and end-walls 13 and 14. The said walls are all integrally connected by a bottom-wall 15.

Secured to the upper portion of the rear-wall 12 just referred to, by means of hinges 16 and 17, is a cover-plate 18. The end-wall 13 is formed with an upwardly-opening clearance-notch or -passage 19 which is in alignment with a similar clearance-notch or -passage 20 in the complementary end-wall 14.

Substantially centrally, the bottom-wall 15 of the tank 10 has connected thereto in a fluid-tight manner, a pipe 21 opening into the interior of the said tank 10 and leading from any suitable source of compressed air or other suitable gas.

A strand 22 to be coated, extends through the aligned clearance-notches 19 and 20 of the tank 10. The said tank may be charged with any suitable froth-producing coating liquid 23 such, for instance, as an aqueous solution of ordinary water-soluble soap, sulphonated-alcohol or pine oil. The upper surface of the liquid 23 is at a level well below the bottom edges of the clearance-notches 19 and 20, and preferably substantially as illustrated in Fig. 3. Air or other suitable gas may now be forced through the pipe 21 upwardly through the froth-producing liquid 23 in the bottom of the tank 10, to create the body of froth or bubbles 24 schematically illustrated in the upper portion of the said tank in Fig. 3.

Preferably, two baffle-plates 25 and 26 are respectively mounted in the respective opposite end-portions of the tank 10, as is especially well shown in Fig. 3. The baffle-plate 25 extends parallel with the end-wall 13 and between the front-wall 11 and rear-wall 12, though spaced slightly inwardly with respect to the said end-wall 13. In its upper edge, the baffle-plate 25 is formed with an upwardly-opening clearance-notch 27 similar to the clearance-notches 19 and 20 before referred to and in alignment therewith longitudinally of the structure. The lower edge 40 of the baffle-plate 25 extends parallel with, but is spaced slightly above the bottom-wall 15 of the tank to permit the flow of the fluid 23. The baffle-plate 26 extends from front to rear between the front-wall 11 and the rear-wall 12 45 of the tank in parallelism with the adjacent end-

wall 14, but spaced inwardly therefrom. Like the baffle-plate 25, the baffle-plate 26 is formed in its upper edge with an upwardly-opening clearance-notch 28 aligned with the clearance-notches 19, 20 and 27 before referred to. The lower edge of the baffle-plate 26 is also spaced above the bottom-wall 15 to permit the flow of the fluid 23.

The strand 22 or its equivalent may be conveniently located in the apparatus by raising the cover-plate 18 and moving the said strand 22 laterally downwardly into the clearance-notches 19, 20, 27 and 28.

Now, when the strand 22 is moved lengthwise by any suitable means, it will pass through the froth or bubbles 24 and will receive on its surface an exceedingly-thin coating which will effectively reduce the adhesiveness or tackiness of the surface of the said strand and thus enable the same to be wound upon a reel without danger of adherence between convolutions.

After emergence from the tank 10 with its film-like coating, the strand 22 or its equivalent should preferably be held in a suspended condition until the coating is dry. The coating of bubbles produced from water-soluble soap and similar froth-producing materials will effectively dry in a fraction of a minute.

The tacky material may vary widely in character from ordinary rubber through synthetic rubber and other polymers and copolymers, all of which are of rubbery character and, hence, insoluble in the aforesaid coating-liquid. A froth-producing substance such as pine oil, for instance, would preferably not be employed in reducing the tackiness of the surface of some materials such, for instance, as ordinary rubber, though suitable for rubber-like materials such, for instance, as neoprene and Buna-N.

In instances where insulated wire of copper or the like has its insulating covering extruded thereon at a relatively high temperature, the insulating material will usually maintain enough heat upon emergence from the tank 10 with its film of adhesiveness-reducing material, to effect the very rapid evaporation of the solvent in the said film.

By means of the present invention, it becomes unnecessary to employ soapstone or other powdery material which contaminates the air and is injurious not only to the health of the operators but is also injurious to adjacent machinery. Furthermore, instead of applying the adhesiveness-reducing material in a liquid form to the material to be treated, the application in froth or bubble form not only minimizes the consumption of material but avoids untidy conditions around the equipment and produces a film which is so thin as to rapidly dry while still being amply effective for the purpose intended.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In the process of manufacturing a strand of rubbery material having a tacky surface: the method of applying a quick-drying coating film to the tacky surface of a continuous length of said strand to permit said strand to be wound on a reel without adherence between successive

convolutions, comprising the steps of providing a body of coating foam supported on the surface of a body of foam-producing tackiness-reducing coating liquid which is a nonsolvent for the said rubbery material; and then passing said continuous length of strand through said foam to cover the tacky surface of said strand with a quick-drying tackiness-reducing coating film.

2. In the process of manufacturing a strand of rubbery material having a tacky surface: the method of applying a quick-drying coating film to the tacky surface of a continuous length of said strand to permit said strand to be wound on a reel without adherence between successive convolutions, comprising the steps of bubbling a gas through a body of foam-producing tackiness-reducing coating liquid which is a nonsolvent for the said rubbery material to produce a body of coating foam supported on the surface of said body of coating liquid; and then passing said continuous length of strand through said foam to coat the tacky surface of said strand with a quick-drying tackiness-reducing coating film.

3. In the process of manufacturing a strand of rubbery material having a tacky surface: the method of applying a quick-drying coating film to the tacky surface of a continuous length of said strand to permit said strand to be wound on a reel without adherence between successive convolutions, comprising the steps of providing a body of saponaceous foam supported on the surface of a body of saponaceous liquid; and then passing said continuous length of strand through said saponaceous foam to cover the tacky surface of said strand with a quick-drying saponaceous coating film.

4. In the process of manufacturing a strand of a rubber-base material having a tacky surface: the method of applying a quick-drying saponaceous coating film to the tacky surface of a continuous length of said rubber-base strand to permit said rubber-base strand to be wound on a reel without adherence between successive convolutions, comprising the steps of providing a body of saponaceous foam supported on the surface of a body of saponaceous liquid; and then passing said continuous strand of rubber-base material through said saponaceous foam to cover the tacky surface of said strand of rubber-base material with a quick-drying saponaceous coating film.

5. In the process of manufacturing a strand of a synthetic rubber material having a tacky surface: the method of applying a quick-drying pine oil coating film to the tacky surface of a continuous length of said synthetic rubber strand to permit said synthetic rubber strand to be wound on a reel without adherence between successive convolutions, comprising the steps of providing a body of pine-oil foam supported on the surface of a body of foam-producing pine oil; and then passing said continuous strand of synthetic rubber material through said pine oil foam to cover the tacky surface of the strand of synthetic rubber material with a quick-drying pine oil coating film.

6. In the process of manufacturing a strand of a rubber-base material having a tacky surface: the method of applying a quick-drying saponaceous coating film to the tacky surface of a continuous length of said rubber-base strand to permit said rubber-base strand to be wound on a reel without adherence between successive convolutions, comprising the steps of bubbling a gas through a body of liquid soap solution to produce

a body of soap bubbles supported on the surface of said body of liquid; and then passing said continuous strand of rubber-base material through said body of soap bubbles to coat the tacky surface of said strand of rubber-base material with a quick-drying saponaceous coating film.
